UNITED STATES PATENT OFFICE.

FREDERICK WRIEDT, OF ALPHINGTON, VICTORIA, AUSTRALIA, ASSIGNOR TO MILO MACHINERY COMPANY PROPRIETARY LIMITED, OF MELBOURNE, VICTORIA, AUSTRALIA.

CRUSHING AND GRINDING MILL.

Application filed June 7, 1922. Serial No. 566,540.

To all whom it may concern:

Be it known that I, FREDERICK WRIEDT, residing at 50 Broomfield Avenue, Alphington, in the State of Victoria, Commonwealth of Australia, have invented certain new and useful Improvements in Crushing and Grinding Mills; and I do hereby declare the following to be a full, clear, and exact description of the invention such as will enable others skilled in the art to which it appertains to make and use the same.

This invention relates to an improved crushing and grinding mill for the treatment of granular materials or substances especially those having an organic nature or character such as grain, beans, seed, or the like; and it has been devised particularly to provide means whereby such materials may be rapidly disintegrated and pulverized continuously and efficiently to a state of fineness or division.

In this invention the material to be treated becomes entrapped between the contiguous surfaces of a stationary supporting surface and one or more movable grinding elements and is thereby broken up and pulverized. The grinding elements are yieldingly pressed against the stationary supporting surface and as the material penetrates therebetween the grinding elements are forced away from the stationary supporting surface in opposition to a retractive force such as the resilient action of a spring, or centrifugal action, or a combination of such actions.

Salient features of the invention reside in the provision of means whereby the entry of material between the stationary surface and movable grinding elements is facilitated, and of means whereby the efficiency of the grinding operation is increased and the movable elements are enabled to transfer or displace the material in a direction transversely to the direction of their motion. The leading portions of such movable element is, chamfered or inclined at a required angle to the stationary supporting surface thereby forming a cuneiform space into which the material can readily enter. Moreover, the movable elements can be furnished with grooves or channels of tapered or other required form to increase the efficiency of the grinding action, and if these grooves or channels are disposed obliquely to the leading edge of the movable element they will

displace the material transversely to the direction of motion of said elements.

A special feature of the invention consists in the grouping or arrangement of such movable grinding elements in parallel series, the elements of each series being stepped or staggered in relationship to the elements of the adjoining series so that each element of any series is positioned in line with the space separating adjacent elements in the next series.

The obliquely disposed grooves on the elements comprising such parallel series can be inclined in a common direction so that the material supplied to one side of a group of movable elements will be displaced transversely to their direction of motion and be discharged at the opposite side thereof into the spaces between adjacent grinding pads in the next series.

In one practical embodiment of the invention the stationary supporting surface can be arranged as a cylindrical casing around the inner periphery of which the movable elements consisting of a plurality of rotating grinding pads or shoes are adapted to travel. The rotating pads are arranged in parallel series and mounted upon a common operative shaft and they can be normally held in contact with the casing by springs, and said pads can be pivoted or otherwise mounted in order that the actions of the springs may be assisted by centrifugal forces if so required.

The material can be subjected to preliminary crushing or breaking down before being exposed to the pulverizing action of the rotating grinding pads and for this purpose crushing or abrading discs are employed one of which is mounted on the operative shaft carrying the grinding pads, and the other on the end of the cylindrical casing.

In a modification of the invention tapered grinding rollers may be mounted upon the operative shaft in lieu of the grinding pads or they may be used in conjunction therewith in required combination. These rollers bear yieldingly against the inner periphery of the casing and in consequence of the differential motion of their peripheries are very efficient for reducing the material to a finely powdered condition.

In order that the invention the object and nature of which have been set forth, may be

readily understood, reference will now be had to the accompanying sheets of explanatory drawings wherein:—

Figure 1 is a view in longitudinal section of a grinding mill constructed in accordance with the present invention.

Figure 2 is a view in transverse section taken on the dotted line 2—2 of Figure 1.

Figure 3 is a view in elevation of the right hand end of the machine shown in Figure 1.

Figures 4 and 5, are views in perspective of grinding pads adapted for pivotal mounting.

Figure 6 is a sectional view of portion of a grinding machine showing a radially guided grinding pad.

Figure 7 is a sectional view of portion of a grinding machine showing a rotatably mounted tapered grinding roller.

In these drawings the numeral 10 designates a hollow cylindrical casing having covers 11 and 12, secured to its opposite ends, the assemblage of said casing and covers forming a closed cylindrical vessel 13, hereinafter termed the pulverizing chamber. The pulverizing chamber 13 is supported at a convenient elevation upon brackets or legs 14 which are connected integrally or otherwise to the covers 11 and 12 as illustrated in Figure 1. If preferred, the brackets 14 can be fixed to or formed integrally with the casing 10 so that the end covers may be easily removed without disturbing the alignment of said casing.

An operative shaft 15 supported in bearings 16 passes axially through the pulverizing chamber and this shaft is provided with fast and loose belt pulleys 17 and 18 and with thrust bearings 19.

One or more spiders 20, conveniently made as grooved or channeled castings or forgings are rigidly fixed to the shaft 15, and upon pins 21 fixed in the spiders 20 are pivotally mounted grinding pads or shoes or blades 22. These grinding pads are normally maintained in contact with the inner periphery of the casing 10 by springs 23 having one of their ends secured to pins 24 on the spiders 20, and suitable means can be provided for adjusting the tension of said springs.

During the operation of the mill the springs 23 cause the pads 22 to exert a yielding pressure against the interior of the casing 10, and this pressure may be augmented by centrifugal action by suitably forming and supporting the pads 22. If the grinding pads 22 are formed so that under centrifugal action they tend to turn in an outward direction about the pivot pins 21 the pressure exerted by them upon the inside of the casing 10 will depend upon the speed at which the shaft is driven.

The pads 22 can, however, be so constructed and arranged that when they are in

contact with the inner periphery of the casing 10, their centres of gravity or mass will lie in radial planes passing through the pins 21 and the axis of the shaft 15 in which case the pressure between the pads 22 and the casing 10 will be independent of the velocity and consequently of centrifugal action, and this pressure which is then due only to the actions of the springs 23 will be approximately constant at all speeds.

The material, for example cocoa beans, to be pulverized become entrapped between the grinding pads 22 and the inner surface of the casing 10; and as the material penetrates therebetween the grinding pads 22 are forced away from the casing against the retractive action of the springs 23 which may or may not be assisted by centrifugal action above described. The grinding pads 22 accordingly ride upon or pass over the material which is thereby subjected to a combination of squeezing and grinding actions and is effectively crushed and pulverized.

In order to facilitate the entry of material between the grinding pads 22 and the casing 10, the leading portions of the former are chamfered or beveled as shown in Figures 2 and 4; to form cuneal spaces 25 into which the material can readily enter. The chamfer or bevel on the pads can be made straight or such chamfering or beveling can be formed to a required curvature.

The efficiency of the grinding action of the pads 22 is greatly increased by providing portion of their working faces with a plurality of tapered grooves or channels 26. The grooves or channels 26 may be formed only in the chamfered portions of the pads 22, and they have a maximum section at the leading edge thereof and gradually decrease in size toward and terminate at the line of junction of the chamfered and contact portions of said pads.

The grooves or channels 26 may be arranged parallelly to the ends of the grinding pads 22 if required, but in practice it has been found that their action is greatly improved if they are set obliquely to the leading edges of said pads. Moreover, by forming said grooves obliquely they serve to displace or move the material transversely to the direction of motion of said grinding pads and the material will be displaced or moved towards the ends of the pads towards which said grooves incline.

The grooves or channels 26 may vary in obliquity and in form, number, extent, and arrangement in any required manner and their number and length may vary in different parts of a pad 22, and they may be more numerous at one end thereof than at the opposite end to suit particular working conditions or materials.

In Figure 5 a grinding pad is shown the

surface of which conforms throughout to the curvature of the casing 10, and in which tapered grooves 27 are formed to facilitate the entry of material in lieu of 5 chamfering the leading portions of said pad. These grooves 27 likewise increase the efficiency of the grinding actions and when disposed obliquely as shown serve to displace the material transversely in a similar 10 manner to the tapered grooves or channels 26.

The grinding pads are arranged in series in parallel planes, preferably in staggered relation, the pads of each series being positioned 15 opposite to the spaces between adjacent pads of each adjacent series. Moreover, the ends of each pad of a series, preferably, project into the spaces between the pads in the adjacent series; the opposite ends 20 of each pad accordingly overlapping or being positioned in the path or line of motion of the adjacent series.

The grooves or channels 26 and 27 can be varied in form and extent in the different 25 series; and may decrease in length in the successive series, preferably being of maximum length at the intake end of the pulverizing chamber 13. The widths of the chamfered portions of the pads in the successive 30 series may likewise diminish and the widths of the contact portions thereof correspondingly increase.

The grooves or channels 26, are preferably inclined in the same direction throughout 35 the different series, and accordingly each series in addition to grinding the material simultaneously displaces it laterally and feeds it into the spaces between adjacent grinding pads in the succeeding series.

40 The material, in this manner, is reduced in successive stages to a required state of fineness and is simultaneously displaced and transferred gradually from one end to the other of the pulverizing chamber.

45 A discharge outlet 28 is provided in the end cover 12 towards which the common inclination of the grooves or channels 26 is directed, and this outlet 28 is preferably furnished with a lateral chute 29 for convenient delivery of the pulverized material to a desired point.

The cover 11 opposite that provided with the discharge outlet is furnished with a feed hopper 30 into which the material to be 50 ground and pulverized is placed and the said material gravitates from this hopper into a supply chamber 31 disposed concentrically about the shaft 15.

55 A plurality of obliquely disposed or helical impelling blades or vanes 32 are fitted to the portion of the shaft which passes through the supply chamber 31 and these blades or vanes serve to thrust the material axially through the supply chamber and 60 into the pulverizing chamber.

The material may be crushed and partially disintegrated before it is delivered to the pulverizing chamber and for simplicity and ease of handling the mill can be provided with crushing or abrading discs 33 70 and 34 which function to preliminarily break down the material during its passage from the feed hopper to the said pulverizing chamber.

The crushing or abrading discs are located in the feed ends of the machine and the disc 33 is rigidly secured to the cover 11 in any approved way and the coacting disc 34 is fixed to the shaft 15 by keys or like means.

These discs 33 and 34 are dished conically on their inner sides and their conical faces are furnished with radially disposed bars or ribs arranged in any approved way. The discs 33 and 34 are set at a predetermined 85 distance apart, and the tapered annular space therebetween has a maximum width at the inner portions of said discs and uniformly diminishes or tapers to the outer portions thereof whereat it attains its minimum width in a peripheral opening 37.

The material is delivered by the impelling blades 32 through a central hole in the disc 33 into the radially tapering space 36 and becoming closely packed therein by centrifugal action it is crushed and disintegrated by 95 the abrading faces of the said discs.

The crushed material emerges from the peripheral opening 37 and passes into the pulverizing chamber wherein it undergoes 100 further treatment and is completely pulverized as previously described.

The material when closely packed between the discs 33 and 34 and when being disintegrated thereby reacts upon said discs in 105 such manner as to force them apart, thereby placing an end thrust on the shaft 15 which is taken by the thrust bearings 19. The degree of fineness to which the material is reduced by the discs 33 and 34 depends upon 110 the distance they are spaced apart, and the said distance can be regulated as required by adjusting nuts 35 on the ends of the shaft 15 as required.

In lieu of the grinding pads 22, tapered or 115 conical rollers 38 as shown in Figure 7 may be employed either alone or with said pads and an efficient combination consists of a plurality of series of grinding pads 22 with a terminal series of said tapered rollers. 120 The rollers 38 are rotatably mounted on arms 39 pivoted on collars or flanges 40 fixed to the shaft 15, and springs are employed to maintain the rollers bearing yielding against the casing 10 in the manner 125 previously described.

The tapered rollers 38 when moving in contact with the surface of the casing 10 have a differential motion about their axes which causes them to skid or slip upon the 130

surface of the said casing and thereby subject the material to an efficient grinding action. The rollers, moreover, in consequence of their conical construction, exert a 5 translatory action on and causes the material to move parallelly to their axes and transversely to their path of motion in a similar manner to the pads 22 previously described.

The tapered rollers can be placed in line 10 with the axis of the pulverizing chamber or slightly obliquely thereto as preferred.

The pads and rollers have been described as pivotally mounted, but if preferred said 15 pads and arms supporting the rollers can be formed with stems 43 which are adapted to be slidably mounted in radially disposed pockets or recesses 42 in collars or flanges 41 formed on or fitted to the operative shaft (see Figure 6). Springs 44 are disposed in 20 the bottoms of the pockets and serve to yieldingly press the pads or rollers against the casing and normally maintain them in contact therewith as previously described.

During the treatment of the material a 25 considerable amount of heat is evolved, which if not removed will with some materials so effect its nature as to prevent the efficient grinding and pulverizing of the same.

30 The temperature of the mill and the material being treated may be maintained with required limits by water cooling or by other suitable means and for this purpose the casing 10 is provided with a jacket 45 the 35 space 46 therebetween being adapted for circulation of water. Likewise the cover 11 on the feed end of the pulverizing chamber is furnished with a jacket 47 to prevent the 40 overheating of the material as it is being acted upon by the abrading discs. During the operation of the machine water is supplied to the jackets 45 and 47 and is passed therethrough and removed therefrom by 45 suitably arranged pipes as 48, 49 and 50.

A mill constructed as above described embodies every feature of my invention and will be found thoroughly efficient in operation but as I am aware that various alterations and modifications may be made therein 50 without departing from the spirit and scope of the same I do not wish to be understood as limiting myself by the positive terms employed in the description, excepting such as the state of the art may require.

55 I claim:

1. In a grinding mill, a stationary support for material to be ground provided with a peripheral concave grinding surface, and a series of grinding elements movable 60 over the support, said grinding elements having convex peripheral grinding surfaces being provided with means for facilitating the entry of material between the grinding elements and the support, and with means 65 for displacing the material transversely to

the direction of motion of the grinding elements.

2. In a grinding mill, a stationary support for the material to be ground, provided with a peripheral concave grinding surface, 70 a series of parallel grinding elements movable over said support, and means for exerting a yielding pressure between the grinding elements and the support, said grinding elements having convex peripheral grinding 75 surfaces provided with means for facilitating the entry of material between the grinding elements and said support, and with means for displacing the material transversely to the direction of motion of said 80 grinding elements and from one end to the other of said support.

3. In a grinding mill, a stationary support for the material to be ground provided with a peripheral concave grinding surface, 85 and a series of parallel staggered and overlapping grinding elements movable over said support, said grinding elements having convex peripheral grinding surfaces provided with means for facilitating the entry of material 90 between the grinding elements and said support, and with means on each grinding element for displacing the material transversely into the space between adjacent grinding elements of the adjoining series.

4. In a grinding mill, a stationary support for the material to be ground, one or more grinding pads, springs for pressing the grinding pads yieldingly against said support and driving means for propelling the 100 grinding pads over said support, said grinding pads being beveled on their leading faces, forming cuneal spaces between said leading faces and said support, and with grooves formed obliquely in the grinding pads. 105

5. In a grinding mill, a stationary support in the form of a cylindrical casing for material to be ground, grinding pads contacting with the cylindrical casing, springs maintaining a yielding pressure between the 110 grinding pads and the cylindrical casing, and an operative shaft for propelling said grinding pads around said cylindrical casing, said grinding pads being provided with oblique grooves and being beveled on their 115 leading edges, forming cuneal spaces between them and said casing.

6. In a grinding mill, a cylindrical casing having an internal peripheral grinding surface, grinding pads contacting therewith, 120 and an operative shaft for propelling the grinding pads around said casing; said grinding pads having convex peripheral grinding surfaces provided with oblique grooves which have a common inclination 125 towards one end of the casing, said casing having a discharge opening at the end towards which the grooves incline and a supply opening at the opposite end.

7. In a grinding mill, a combination of a 130

- cylindrical casing having an internal arc-shaped concave grinding surface, and a plurality of series of yieldingly supported grinding pads having convex peripheral 5 grinding surfaces and adjacent thereto leading non-contact portions provided with oblique grooves, and an operative shaft for propelling said grinding pads around said casing; said grooves and non-contact 10 faces decreasing in length and width respectively in the pads of each series as they are located progressively nearer the discharge end of the pulverizing chamber.
8. A grinding mill having a cylindrical 15 pulverizing chamber, having a cover at one end, provided with a centrally disposed supply opening, and a supply chamber connected therewith, a driving shaft carrying grinding means within said cylinder, said 20 shaft being extended through said opening and supply chamber, a conically dished grinding disc fixed to said cover and con-
- centrically located about said supply opening, a similar grinding disc fixed to the driving shaft, said grinding discs having 25 abrading surfaces on their conical faces and a peripheral discharge opening within said pulverizing chamber between them, and impelling blades fixed to the driving shaft and located in said supply chamber. 30
9. In a grinding mill, a grinding pad having a chamfered leading portion, and obliquely disposed tapered grooves in the said chamfered portion.
10. In a grinding mill, a yieldingly sup- 35 ported grinding pad having grooves formed obliquely to its leading edge.

In testimony that I claim the foregoing as my invention, I have signed my name in presence of two subscribing witnesses.

FREDERICK WRIEDT.
